UNITED STATES PATENT OFFICE.

IRA M. CLARKE, OF NEW MARTINSVILLE, WEST VIRGINIA, ASSIGNOR TO THE NEW MARTINSVILLE GLASS MFG. CO., OF NEW MARTINSVILLE, WEST VIRGINIA, A CORPORATION OF WEST VIRGINIA.

DESIGN FOR A SECTIONAL JAR.

Application filed July 16, 1923. Serial No. 6,787. Term of patent 7 years.

To all whom it may concern:

Be it known that I, IRA M. CLARKE, a citizen of the United States, residing at New Martinsville, in the county of Wetzel and State of West Virginia, have invented a new, original, and ornamental Design for Sectional Jar, of which the following is a specification, reference being had to the ac-

companying drawing, forming part thereof, in which the figure is an elevation of a sectional jar embodying the present design.

I claim:—

An ornamental design for a sectional jar as shown.

IRA M. CLARKE.
